UNITED STATES PATENT OFFICE.

ROBERT E. BURKE, OF HOBOKEN, NEW JERSEY.

VALVE.

No. 825,705.

Specification of Letters Patent.

Patented July 10, 1906.

Application filed December 20, 1905. Serial No. 292,637.

To all whom it may concern:

Be it known that I, ROBERT E. BURKE, a citizen of the United States, residing at Hoboken, in the county of Hudson and State of New Jersey, have invented certain Improvements in Valves, of which the following is a specification.

This invention is an improvement in valves, and relates more especially to the class of engineers' valves which are employed in connection with air-brake systems.

The principal objects of the invention are to provide a peculiar form of cylindrical valve which shall be simple and cheap in construction, durable in use, easily operated, and in which the disposition of the cavities in the cylindrical plug or valve proper is such with respect to the intake and outlet openings in the casing or cylinder as to insure at all times a proper seating of the plug or valve proper without the employment of the usual springs.

With these general objects in view the invention consists in the particular construction and arrangement of parts constituting the valve, all as hereinafter fully described, and more specifically set forth in the appended claims.

In the accompanying drawings, which form a part of this specification, Figure 1 is a longitudinal sectional view through the center of a valve constructed in accordance with my invention. Fig. 2 is a transverse sectional view on the line 2 2 of Fig. 1. Fig. 3 is a front end view of the valve with the covering-plate removed to show the manner of connecting the cylindrical plug or valve proper and its stem.

Like numerals of reference indicate like parts in all the figures of the drawings.

Though primarily intended as an engineer's valve for air-brake systems, it will be obvious that my improved form of valve may be used wherever a three-way valve is desired for the purpose of regulating the flow of any fluid-pressure.

In carrying out my invention I employ, in the first place, a valve-casing 1, having the cylindrical chamber 2 and provided with the intake-opening 3 for the fluid-pressure and

50 with openings 4 and 5, the opening 4, which is adjacent the intake, being adapted to connect with the train-pipe of an air-brake system or other conduit 6, while the opening 5, which is just beyond said opening 4, connects 55 with an exhaust-pipe, as 7. Where the openings 4 and 5 extend through the casing the

latter may be enlarged, as shown, to provide a flat surface against which is bolted the plate 8, carrying the nipples for convenience in connecting the train and exhaust pipes hereinbefore mentioned.

In forming the valve-casing the cylindrical chamber is preferably bored all the way through and is afterward closed at its ends by the plates or heads 9 and 10; through one 65 of which, as 9, the valve-stem passes, for which purpose said plate or head is provided with the usual stuffing-box 11. The plates or heads 9 and 10 are secured to the casing by means of bolts or other fastenings; but it 70 is obvious that instead of having both heads removable one of them may be formed integrally with the body of the casing, if desired.

12 designates the rotatable cylindrical plug or valve proper, which in the present instance is of slightly less diameter than that of the cylindrical chamber, so as to fit loosely therein and be forced closely against one side thereof under fluid-pressure. In one side of this cylindrical plug or valve proper there is 80 a cavity 13, which is semicircular in shape and of such width at its outer end as to extend from the outer side of the opening 4 to the outer side of the opening 5, (see full lines, Fig. 2,) so that when the plug is in this position said openings will be in communication and the wall of the cylindrical plug or valve proper will close communication between either of said openings and the intake-opening 3. It will also be noted that the location 90 of the intake-opening 3 with respect to the train-pipe opening 4 is such that when the cylindrical plug or valve proper is turned to the position indicated in dotted lines in Fig. 2 the cavity 14 will establish communication between the intake-opening and the train-pipe, the exhaust-opening 5 being closed by the wall of the cylindrical plug or valve proper. Furthermore, when said cylindrical plug or valve proper is turned to a 100 point intermediate the positions shown in the drawings—that is, with the wall closing the opening 4—the valve will be entirely closed and will be perfectly seated by the force of the fluid-pressure.

As heretofore stated, the cylindrical plug or valve proper fits loosely in the chamber of the valve-casing, so that it will not bind and may be easily turned, and in order to provide that said cylindrical plug or valve proper 110 will seat snugly and firmly to prevent escape or leakage of the fluid-pressure in the opera-

tion of the valve in either position thereof I locate the cavity 14, hereinbefore referred to, directly opposite the semicircular cavity 13, and said cavity 14 is formed by cutting away 5 nearly one-half of the cylindrical plug or valve proper, leaving the transverse wall 15, the ends of which latter abut against the walls of the casing. The bottom of the cavity 14 is preferably inclined upwardly from 10 each side to the center, so as not to weaken the wall 15 on a line with the cavity 13. It will be readily seen that by providing the cavity 14 opposite the cavity 13 the former cavity will receive the fluid-pressure from the 15 intake-opening 3 in any of the aforementioned positions of the cylindrical plug or valve proper, and the pressure being confined between the wall 15 of the cylindrical plug and the opposite wall of the casing will 20 cause the ends of said wall to abut snugly against the casing and provide a close-fitting seat, thereby preventing leakage.

By the particular construction of valve-casing and cylindrical plug or valve proper I 25 provide a closely-seating valve through the medium of the force of the fluid-pressure which passes to the valve, and thereby dispense with the usual springs and the tapered form of valve-plug. This not only simplifies 30 the valve and reduces its cost, but also reduces friction, making it easier to operate and requiring considerably less lubricating-oil. Furthermore, inasmuch as the cylindrical plug or valve proper is seated by the 35 force of the fluid-pressure any wear thereon is taken up by such pressure.

The cylindrical plug or valve proper may be operated or turned by any suitable means, in the present instance by the handle 16, connected to or formed integrally with the valve-stem 17, the latter being attached to the cylindrical plug or valve proper. In attaching the stem to the cylindrical plug or valve proper I provide the former with a cross-head, as 18, and insert the same in a corresponding recess, as 19, in the end of the cylindrical plug or valve proper, the parts being held in connection when the head 9 is bolted in place. By forming the valve-stem and 50 cylindrical plug or valve proper separately, as described, either part may be renewed at small expense, and the same advantage is gained by making the valve-casing of several separable parts.

55 Having thus described my invention, what I claim as new, and desire to secure by Letters Patent, is—

1. In a valve of the character described, the combination with a casing having a cylindrical chamber therein, an intake-opening, an outlet-opening adjacent the intake-opening and a second outlet-opening beyond the other outlet, of a cylindrical plug or valve proper rotatable in the chamber of the casing and having cavities at opposite sides, one

of said cavities communicating with the intake-opening in any of the positions of the valve, substantially as shown and described.

2. In a valve of the character described, the combination, of a casing having a cylindrical chamber therein, an intake-opening, and outlet-opening adjacent the intake-opening and a second outlet-opening beyond the aforesaid outlet-opening, a cylindrical plug or valve proper rotatable in the chamber of the valve-casing and having cavities at opposite sides its transverse center, and means for turning the cylindrical plug or valve proper.

3. In a valve of the character described, the combination, with a casing having a cylindrical chamber therein, an intake-opening and a pair of outlet-openings, of a cylindrical plug or valve proper rotatable in the chamber of the valve-casing having a semicircular cavity at one side and at the other side a cavity occupying nearly one-half of said cylindrical plug leaving a transverse wall, whereby the latter cavity communicates with the intake-opening in all the positions of the valve to cause the fluid-pressure to seat the valve, substantially as shown and described.

4. In a valve of the character described, the combination with the valve-casing having a cylindrical chamber therein, an intake-opening and outlet-openings, of a cylindrical plug or valve proper comprising cylindrical ends and a connecting-wall, the latter extending transversely to form cavities at opposite sides thereof, substantially as shown and for the purpose set forth.

5. In a valve for the purposes set forth, the combination with the valve-casing having a cylindrical chamber therein, an intake-opening and outlet-openings, of a cylindrical plug or valve proper comprising cylindrical ends and a connecting-wall extending transversely between said ends forming cavities at opposite sides of said wall, the bottom of one of said cavities approximating the diameter of the cylindrical plug or valve proper.

6. In a valve of the character described, the combination with the valve-casing having a cylindrical chamber therein, an intake-opening and a pair of outlet-openings, said outlet-openings being adjacent each other, of a cylindrical plug or valve proper having cavities in opposite sides and a transverse recess in one end, and a valve-stem having a cross-head engaging said recess.

7. In a valve of the character described, the combination, of a casing provided with a cylindrical chamber, an intake-opening and outlet-openings, a removable head forming one end of the casing and having an opening for the valve-stem, a cylindrical plug or valve proper rotatable in the chamber and having cavities in opposite sides and a transverse recess in one end, and a valve-stem projecting through the opening in the removable head of

the casing and provided with a cross-head engaging the transverse recess of the cylindrical plug or valve proper.

8. In a valve of the character described, 5 the combination, of the casing 1 having the cylindrical chamber 2, intake-opening 3 and outlet-openings 4 and 5, removable heads 9 and 10 forming the ends of the casing, a cylindrical plug or valve proper 12 having the 10 semicircular cavity 13 at one side and the deeper cavity 14 at the other side, the latter communicating with the intake-opening in all the positions of the valve, said cylindrical

plug having a transverse opening at one end, and a valve-stem extending through one of 15 the heads of the casing and having a cross-head engaging the transverse opening in the cylindrical plug or valve proper, as herein shown and described.

In testimony whereof I have signed my 20 name to this specification in the presence of two subscribing witnesses.

ROBERT E. BURKE.
